[57] CLAIM

The ornamental design for a vacuum cleaner, as shown and described.

DESCRIPTION

FIG. 1 is a front elevational view of a vacuum cleaner showing our new design;

FIG. 2 is a side elevational view thereof;

FIG. 3 is a rear elevational view thereof;

FIG. 4 is a side elevational view of the opposite side of FIG. 2;

FIG. 5 is a top plan view thereof;

FIG. 6 is a bottom plan view thereof; and

FIG. 7 is a top, front and side perspective view thereof;

The cross-hatch pattern shown on the vacuum cleaner bag in all views is understood to repeat throughout the indicated area.

FIG.1

FIG.2

FIG. 5

FIG. 6

FIG. 7
